CHANDELIER

Edward Walter Poerner, East Orange, N. J., assignor of one-half to David Tunick, Newark, N. J.

Application February 21, 1950, Serial No. 8,051

Term of patent 7 years

(Cl. D48—23)

To all whom it may concern:

Be it known that I, Edward Walter Poerner, a citizen of the United States of America and a resident of East Orange, county of Essex, and State of New Jersey, have invented a new, original, and ornamental Design for a Chandelier, of which the following is a specification, references being had to the accompanying drawing, forming a part thereof.

In the drawing:

Figure 1 is a perspective view of a chandelier, showing my new design;

Figure 2 is a fragmentary horizontal section on the line 2—2 of Figure 1, at a larger scale, showing the chandelier body and two of the vertically extending lamp shields.

The chandelier is symmetrical about its vertical axis.

I claim:

The ornamental design for a chandelier, as shown and described.

EDWARD WALTER POERNER.
